(57) **CLAIM**

The ornamental design for a valve, as shown and described.

DESCRIPTION

FIG. 1 is a top perspective view of a valve showing my new design;

FIG. 2 is a front view thereof;

FIG. 3 is a rear view thereof;

FIG. 4 is a left view thereof;

FIG. 5 is a right view thereof;

FIG. 6 is a top plan view thereof shown in a larger scale; and,

FIG. 7 is a bottom plan view thereof shown in a larger scale.

The broken line shown in the figures are included for the purpose of illustrating portions of the valve and form no part of the claimed design.
